United States Patent Office.

JOHN GRACIE AND ROBERT H. BOYD, OF PITTSBURG, PENNSYLVANIA.

Letters Patent No. 77,481, dated May 5, 1868.

IMPROVEMENT IN LAMP-BURNERS.

The Schedule referred to in these Letters Patent and making part of the same.

TO ALL WHOM IT MAY CONCERN:

Be it known that we, JOHN GRACIE and ROBERT H. BOYD, of the city of Pittsburg, in the county of Allegheny, and State of Pennsylvania, have invented a new and useful Improvement in Lamps; and we do hereby declare the following to be a full, clear, and exact description thereof, reference being had to the accompanying drawings, making a part of this specifications, in which—

Figure 1 is a vertical section through a lamp-burner furnished with our improvements, and the lamp or oil-reservoir to which it is attached, and

Figure 2 is a sectional representation of gas-traps attached to the burner.

Like letters of reference indicate like parts.

Our improvement in burners for hydrocarbon burning-fluids is designed to render perfectly safe the use of benzole, naphthaline, and the most volatile of the products of petroleum, for illuminating purposes, by the use of a burner which is equally adapted to the burning of the heavier descriptions of carbon-oil, and also to secure a more perfect control of the supply of air to the flame in such manner as to effect the consumption of all or most all of the carbon and gas which are evolved, and a large amount of which frequently escapes unconsumed, in consequence of the defective construction of the burner used.

To enable others skilled in the art to construct and use our improved burner, we will proceed to explain our invention.

The great danger attending the use of benzine and other light hydrocarbons for burning in lamps, arises from the ease with which they volatilize at low temperatures, resulting in the formation of gas or gaseous vapor in the fluid-chamber or globe of the lamp, which gas, escaping and becoming mixed with atmospheric air, forms a highly-explosive mixture. Were it not for this difficulty, these light hydrocarbons would afford the most desirable fluids for burning, as they give a whiter and more brilliant light than the carbon-oil which has been deprived of its more volatile ingredients. If, therefore, we can furnish a safety-burner which shall render these light burning-fluids innoxious, we effect a most important saving, by utilizing what is now a waste product.

In order to secure the desired object, we prevent the escape of gas up the wick-tube of the lamp, and conduct the gas into a small reservoir, from which it passes through a fine aperture, (too small for the downward passage of fire,) to the flame of the lamp at the top of the wick, where it is at once consumed in a manner to increase the volume of light-giving flame.

The burner-frame is of the shape shown in fig. 1, the upper part, *a*, being shaped like the cone of the ordinary burner, and the lower part, *b*, being considerably enlarged in diameter, and shaped like the cup of an acorn. In the lower part of the burner-frame is a series of large apertures, *c*, for the admission of air. Inside of the burner-frame is a partition, *d*, extending all round from the base of the cone, *a*, or upper part of the burner-frame, to the neck of the burner-frame. This partition is curved in a direction opposite to the lower part of the burner-frame, so as to form an annular cavity, *e*. This partition *d* is perforated with a number of holes, *i*, much smaller than the apertures *c* in the outer part of the frame. The perforated partition *d* is shaped and constructed like the lower part of the ordinary burner-frame. Inside of the outer burner-frame, *b*, is a circular plate, *h*, which fits closely to the inner surface of the burner-frame, *b*, and is furnished with apertures corresponding in size and position with the apertures *c*. This plate *h* has a button, *g*, projecting through a slot in the burner-frame *b*, by which it may be pushed round in the burner-frame far enough to close the apertures *c* in the burner-frame *b*, thus serving as a register to open or close the apertures *c* wholly or partially, and thus regulate the current of air admitted into the interior of the burner. The cone *a* is truncated, the top or apex, *f*, being cut off, and is attached to the crown-piece *k*, which holds the chimney, while the lower portion, *a*, of the cone, forms a part of the burner-frame, as before described. Around the top of the truncated portion of the cone is a flange or annulus, *l*, which serves as a ledge to support the crown-piece *k* and chimney, the crown-piece being pivoted to the ledge or flange *l* by a pin, *n*. By this arrangement the top of the wick is reached for the purpose of trimming the wick or lighting the lamp, by turning the crown-piece on its pivot *n*. The wick-tube *m* passes perpendicularly through the centre of the burner-frame, in the

ordinary way, but instead of terminating at the neck of the lamp, as is usual, it extends downward to or nearly to the bottom of the globe or oil-receptacle of the lamp, so that its lower extremity is always covered with oil when the lamp is in use, thus forming a seal, which prevents the flow or escape of gas from the globe up through the wick-tube.

So much of the wick-tube m as is contained in the globe of the lamp may be made wholly or in part of fine wire gauze. The lower end of the tube m may be made smaller, as shown at z , or its mouth, z' , may be covered with fine wire gauze, to prevent the downward passage of the wick. Thus made, the oil cannot be burned out so as to leave the lower end, z' , of the tube m uncovered, whereby a perfect hydraulic seal is secured.

At the base of the screw-neck, p , being the bottom of the burner-frame, is a diaphragm, q , which is furnished with one or more openings, r , covered with wire gauze, or made of perforations, fine enough to prevent the passage of flame. In place of these gauze-covered openings, small traps, s , shown in fig. 2, may be substituted, which, filled with oil or other fluid, will allow the egress of gas and the ingress of air, but prevent the passage of flame.

The apertures r in the diaphragm q open into a small gas-reservoir, t , covered over at the top by the plate u , but furnished at the sides, all round, with small holes v , which permit the entrance of air, to mingle with the gas or vapor. Around the wick-tube m , (which passes through the gas-reservoir t), is a second or outer tube, w , which opens into the gas-reservoir t , being attached, at its lower end, to the plate u , on top of the reservoir t . This second or outer tube w is parallel or nearly so with the wick-tube m , which it surrounds, and terminates at the top of the wick-tube m , the space between them at the top being narrow, and the draught of air, as hereinafter to be described, preventing the downward passage of air between them, whereby we avoid all danger of the explosion of the gas in the reservoir t . Within the reservoir t is room for the spur-wheel, by which the wick is raised or lowered, but which, to avoid confusion, is omitted in the drawing.

By this construction it is impossible for any gas or gaseous vapor formed in the globe of the lamp by the volatilization of the burning-fluid, to escape into the cavity of the burner-frame, or into the chimney of the lamp, and explode. Any gas or vapor thus generated must pass through the openings r in the diaphragm q , into the reservoir t , whence it is carried, by the current of air entering through the holes v , up the tube w , around the wick-tube m , and is burned as it escapes at the top of the tube, around the top of the wick. This constant current of cold air passing through the reservoir t , and through the tube w , around the wick-tube m , serves to keep the latter cool, and thus prevents the lower portion, m' , which enters the globe of the lamp, becoming so hot as to vaporize the burning-fluid.

A fruitful source of annoyance in carbon-oil lamps is the weeping of oil from the top of the wick, which, running down the wick-tube, collects in the bottom of the burner-frame, and when the lamp is lit, this oil, vaporizing, creates a gas which causes the light to flicker. This is obviated by the use of the outer tube w , surrounding the wick-tube m . The oil which weeps from the wick runs down inside the tube w , and passes into the globe of the lamp, through the holes $r r$.

The small openings in the partition d of the burner-frame are necessary to give a sufficient velocity to the current of air which enters the burner-frame under the cone, but they afford no means of regulating the quantity of air, so that unless the wick is at a particular height, the lamp will smoke, causing a disagreeable smell, but by use of the annular space e , and the register h , the quantity of air can be adjusted so that the carbon and gas will all be consumed.

Having thus described our invention, what we claim as new, and desire to secure by Letters Patent, is—

1. A wick-tube, $m m'$, partially closed at its lower end by an indentation, z , or other equivalent device, substantially as and for the purposes above set forth.
2. An opening or openings leading from the globe or oil-receptacle of a lamp to the inside of the burner, each opening being covered with wire gauze, finely-perforated plate, or provided with a gas-trap, and arranged within the burner, substantially as and for the purposes described.

In testimony whereof, we, the said JOHN GRACIE and ROBERT H. BOYD, have hereunto set our hands.

JOHN GRACIE,
ROBERT H. BOYD.
